UNITED STATES PATENT OFFICE.

WILLIAM RITTBERGER, OF GRANITE CITY, ILLINOIS.

MILL-ROLL LUBRICATOR.

1,150,885.

Specification of Letters Patent.

Patented Aug. 24, 1915.

Application filed September 29, 1914. Serial No. 864,149.

To all whom it may concern:

Be it known that I, WILLIAM RITTBERGER, a citizen of the United States, residing at Granite City, in the county of Madison and

5 State of Illinois, have invented new and useful Improvements in Mill-Roll Lubricators, of which the following is a specification.

This invention is an improved lubricating 10 apparatus for use in lubricating the rolls of an iron rolling mill.

The invention consists in the construction, combination and arrangement of devices hereinafter described and claimed.

15 In the accompanying drawings:—Figure 1 is a side elevation of an iron roller mill provided with a lubricator constructed in accordance with my invention. Fig. 2 is a detail vertical longitudinal sectional view 20 of one of the lubricant reservoirs. Fig. 3 is a vertical sectional view of the same on the plane indicated by the line 3—3 of Fig. 2. Fig. 4 is partly a plan and partly a horizontal sectional view of one of the lubricating boxes. Fig. 5 is a vertical sectional view of the same. Fig. 6 is a detail sectional view of a member of one of the steam jacket pipes. Fig. 7 is a similar view of the telescoping joint in said pipe. Fig. 8 is a transverse sectional view of the same on the plane indicated by the line 8—8 of Fig. 7.

For the purposes of this specification one of the standards of a rolling mill is shown at 1 and the rollers at 2. In accordance with 35 my invention I provide a tank or reservoir 3 for the reception and heating of the lubricant. Under the bottom of this reservoir is a casting 4 to the under side of which nipples 5 are attached, the nipples serving for 40 the attachment of steam jacket and lubricant conveying pipes 6. A steam heating roller 7 is arranged in the reservoir and its ends are connected to the nipples as at 8. Each nipple is divided into a flow duct or 45 passage 9 and a return duct 10, the said return duct being connected together by a passage 11 in the casting or base 4. Each nipple also has a centrally arranged oil passage 12. Said oil passage communicates 50 through openings 13 with the reservoir. The base 4 has a channel 14 in its upper side which extends longitudinally thereof and in this channel are a pair of slides 15 to 55 cut off or open the openings 13 and hence control the supply of lubricant from the reservoir. The steam jacket pipes lead

downwardly from the nipples 5 and are each formed with a flow passage 16 and a return passage 17. Each steam jacket also has a central oil passage 18. The passages 60 of these pipes correspond with the similar passages of the members.

A pair of lubricating boxes 19 which are substantially triangular in shape are arranged on the necks or trunnions of the rolls 65 2 and bear against one side of the vertical opening 20 in the standard 1 and in which the necks of the rolls are mounted. The bearing blocks for the necks of the rolls are indicated at 21. Each lubricating box is 70 provided with a longitudinally arranged steam jacket pipe 22 which has a flow passage 23 and a return passage 24 and is also provided with a centrally arranged lubricating conveying passage 25 which discharges through openings 26 into a distributing box 27 which is arranged longitudinally in the lubricating box, is filled with asbestos or other suitable absorbent 75 28 and is provided at its lower side with lubricant discharge openings 29 and with a slide 30, to open or close said openings. Each box 19 is open on its under side next the neck of the roll in connection with which it operates and is provided in said open side with 80 rollers 31 which bear on the neck of the roll. Each lubricating box is also provided with a water circulating pipe 32 which is preferably covered by asbestos or other suitable material as at 83 the water circulating pipe 90 serving to keep the lubricant cool in the lubricating box. A water feed pipe 34 is connected to the circulating pipe of the lower lubricating box. A water pipe 35 connects the circulating pipes in the lubricating 95 boxes and a water pipe 36 leads from the circulating pipe in the upper lubricating box. It is desirable to keep the lubricant cool in the lubricating box to prevent an excessive application of lubricant to the neck of the 100 roll and also to minimize the heating of the neck roll and lubricating box caused by friction.

Each steam jacket pipe 6 includes a member 37 which is connected to one of the lubricating boxes by an elbow 38, the said members 37 having flow and return passages 16^a—17^a which correspond with those of the steam jacket pipes and being also provided with oil feed passages 18^a which correspond 110 with those of the steam jacket pipes. Each steam jacket pipe also has a telescoping

joint 39 as shown in detail in Figs. 7-8 which render said pipes longitudinally extensible and adapt the lubricating boxes to move vertically to a slight extent and yet 5 remain connected to the reservoir and steam coil to receive lubricant from the pipes for application to the necks of the rolls and permit the circulation of steam through said flow and return ducts of said pipes, said lubricating boxes and the steam coil 7 and thereby keep the lubricant or grease warm in the reservoir and hence keeps the lubricant fluid so that it passes through the pipes to the lubricating boxes and from the latter 10 to the necks of the rolls. A steam feed pipe 40 is attached to the flow passage 16^a of the pipe member 37 of the lower lubricating box and a steam exhaust pipe 41 is attached to the return passage 17^a of said member. 15 Hence the steam is caused to pass first through the steam circulating pipe in the lower lubricating box, from thence up through the flow passage 6 of its pipe 6 to the steam coil 7 from the latter through the flow passage 16 of the other pipe 6 to the 20 upper lubricating box, then through the latter and therefrom back through the return passage 17 of the pipe 6 of said upper lubricating box, the passage 11 of the base 4 and from said passage through the 25 return passage 17 of the pipe 6 of the lower 30

lubricating box and from the member 37 of said pipe out through the exhaust pipe 41 as will be understood.

Having thus described my invention, I claim:—

1. In combination with journals, a lubricating reservoir, lubricating boxes arranged on the journals and pipes connecting said boxes to the reservoirs to supply them with lubricant therefrom, a steam heating coil in said reservoir and steam jacket pipes arranged around the lubricant feed pipes and communicating with the heating coil. 40

2. In combination with journals, a lubricating reservoir, lubricating boxes arranged on the journals and pipes connecting said boxes to the reservoir to supply them with lubricant therefrom, a steam heating coil in said reservoir and steam jacket pipes arranged around the lubricant feed pipes and communicating with the heating coil and water circulating means located in said lubricating boxes and absorbent lubricant applying pads also arranged in said lubricating boxes. 50

In testimony whereof I affix my signature in presence of two witnesses.

WILLIAM RITTBERGER.
